UNITED STATES PATENT OFFICE.

GEORGE J. BROCKHAGEN, OF BROOKLYN, NEW YORK.

CHANGE-MAKING MACHINE.

1,393,424.

Specification of Letters Patent. Patented Oct. 11, 1921.

Application filed January 15, 1919. Serial No. 271,230.

To all whom it may concern:

Be it known that I, GEORGE J. BROCKHAGEN, a citizen of the United States, residing at Brooklyn, in the county of Kings 5 and State of New York, have invented certain new and useful Improvements in Change-Making Machines, of which the following is a specification.

This invention relates to change-making 10 machines, and particularly to a machine in which selected coins will be delivered in exchange for a coin or coins of higher denomination, after deducting a given amount, as one or more fares on a public conveyance. 15 The invention is particularly applicable for use in connection with street cars of that general type known as "pay as you enter" cars, in which the passenger deposits a coin, and in the event of the deposited 20 coin being of a higher denomination than the fare required, receives "change".

The invention is also adapted to be used in connection with a fare register, although the fare register does not necessarily form 25 an essential part of the invention.

The mechanism is so constructed that change may be made for coins of denominations of from ten cents to fifty cents, although for some purposes the mechanism 30 may be moved to render change for different denominations than those just expressed.

In the drawings:

Figure 1 is a vertical longitudinal sectional view through a change-making machine constructed in accordance with my invention;

Fig. 2 is a plan view of the same;

Fig. 3 is a cross-sectional view on the line 40 3-3 of Fig. 1.

Fig. 4 is a cross-sectional view through the line 4-4 of Fig. 1, parts being removed for the sake of clearness;

Fig. 5 is a view partly in section through 45 the actuating shaft, showing the pusher fingers and slide detent dogs;

Figs. 5^a and 5^b are detail views of a clutch mechanism shown in Fig. 5;

Fig. 6 is an edge view of the cam slide;

Fig. 7 is a cross-sectional view on the line 50 7-7 of Fig. 1;

Fig. 8 is an edge view of the multiple dime ejector clutch;

Fig. 9 is a detailed view of the bottom 55 dime ejector;

Fig. 10 is a detailed view of the top dime ejector;

Fig. 11 is a detailed view of the dime ejector clutch lever;

Fig. 12 is a detailed view of another coin 60 ejector slide;

Fig. 13 is a vertical cross-sectional view on the line 13-13 of Fig. 1;

Fig. 14 is a detailed view of an ejector 65 engaging dog;

Fig. 15 is a cross-sectional view through a friction device for the ejectors;

Fig. 16 is a detailed perspective view of the dime ejector clutch mechanism;

Fig. 17 is a perspective view of a key and 70 its correlated mechanism for ejecting a coin of highest denomination;

Figs. 18, 19 and 20 are detail views of the means for automatically limiting the ejection-inducing function to a single coin, when 75 two coins of the same denomination are required in a transaction aggregating more than the value of one of such coins.

In carrying out the invention, I prefer to employ a casing 20, which may be substantially rectangular, and provided with a floor 21 and a subjacent compartment 22, provided with a drawer 23 to receive money fed into the machine. Above the floor 21 is a plurality of coin magazines, designated in 80 Fig. 3 as 24, 25, 26 and 27, for the reception of coins of the denominations of fifty cents, twenty five cents, ten cents and five cents, in the order named. Extending from a point substantially coincident with the top of each 85 magazine, is a guide baffle, these being designated 28 and 29, for a half dollar and a quarter respectively, to direct coins of these denominations through an opening 30 into the drawer 23, the baffle plates 31 and 32, 90 designed for a dime and a nickel, being for the purpose of directing coins of these denominations through the opening 33 into the drawer 23. The bottoms of the magazines are open and coins are adapted to 95 be ejected therefrom into a transversely extending trough 34, from which they may slide into a coin pan 35 in the front of the machine, so as to be accessible to the person originally depositing a coin in the machine. 100 In rear of the magazine, that is, on the conductor side of the casing, is a coin pan 36, having branches 37, 38, 39 and 40, one branch leading to each of the coin openings.

As heretofore indicated, the present machine 110

is designed for coins of four denominations, and therefore there are four coin slides in the rear side of the machine, these being designated 41, 42, 43 and 44, and these slides 5 are provided with openings 45, 46, 47 and 48, and each opening registers with an opening of slightly less diameter in the plate 49, beneath the slides, and with one of the openings 50, 51, 52 and 53 in the top of the casting 20. The purpose of providing the plate 49 with openings slightly less in diameter than those with which they register, is that, when a coin of proper denomination is inserted through one of the openings, the slide 10 15 will carry it over to one of the chutes, to be deposited in the drawer 23; but if a coin of improper denomination is inserted, (as, for example, if a dime is inserted in the place provided for a quarter), the incorrectly inserted coin will find its way to the coin pan 36, so that the conductor may return it to the depositor. Each slide is provided with an operating mechanism, and all of these operating mechanisms are controlled from a 25 single shaft 54, journaled transversely of the casing, and provided with a handle pull 55. One of the operating mechanisms is illustrated in Fig. 1, and as all others are duplicates, it is deemed necessary to describe 30 the one shown only. Each slide is provided with a depending portion 56 having a stud 57 projecting laterally therefrom and extending through a slot 58, in one end of a lever 59, pivoted to the floor 21 at 60. On 35 the shaft 54 is the crank 61, connected to the lever 59 by a link 62, so that when the handle 55 is given a partial turn, anti-clockwise, the crank 61 will move from left to right and project the slide in the direction of the 40 chute, so that the coin can be deposited in the drawer 23. After the handle is turned so as to actuate the slide, both the handle and the slide will be returned to the normal position shown in Fig. 1 by the tension 45 spring 63, one end of which is attached to the floor 21, and the other to the finger 64.

Means is provided for ejecting a coin of lower denomination than the one introduced, when the amount of the fare is less than 50 the denomination of the introduced coin, and the mechanism for accomplishing this is best shown in Figs. 1, 4, 5, 7 and 13. Referring now particularly to Fig. 5, 65 55 designates a shaft journaled in suitable bearings 66 and 67, and rigid on said shaft is a pusher finger 68, the purpose of which will be presently described. The shaft is also provided with an independently rotatable slide 69, at one end of which is a 60 pusher finger 70, and at the other end of which is a dog 71. 72 is a pusher finger rigid on the shaft 65. 73 is a sleeve loose on the shaft 65, and adapted to have longitudinal movement imparted thereto, but 65 held against rotative movement with re-

spect to the shaft 65, by means of the pin and slot connection 74, the construction being such that the sleeve 73 may move out of clutching engagement with the sleeve 75, mounted loosely upon the shaft 65 and 70 carrying the dog 76. The sleeve 75 is provided with clutch faces 77 and 78, adapted to engage complementary faces on the sleeve 73 and on the sleeve 79, the latter being loosely mounted on shaft 65, and carrying 75 at one end a pusher finger 80, and at the other a dog 81. If a partial rotative movement is imparted to the shaft 65, said shaft will be restored to its original position by the finger 82 and its spring 83, similar 80 spring-pressed fingers 84 and 85 being, designed to restore the sleeves 69 and 79 respectively. By reference to Fig. 5 it will be observed that the sleeve 73 is provided with a bar 86 extending longitudinally of 85 the shaft, so as to bridge the sleeve 75, and having a shoulder 87, at times out of contact with the projection 88 on sleeve 79, but under certain conditions adapted to be picked up by projection 88, as will appear 90 hereinafter. The fingers 68, 70, 72 and 80 are adapted to actuate certain pusher rods which respond to said fingers, so as to control certain mechanisms which eject coins from the magazines. The particular time 95 at which any particular coin-ejecting mechanism will operate will be controlled by a cam slide, best shown in Figs. 4 and 6, which operates a pusher rod positioning means. The pusher rods which move in 100 response to the fingers 68, 70, 72 and 80 are normally out of line with their respective fingers, and are adapted to be brought into line with their fingers by pull rods. The pusher rod 89 for releasing nickels is provided with a bifurcated end (Fig. 13) to provide a main finger portion 90 to act in response to finger 68, and an offset portion 91 adapted to receive an impulse from finger 70. The pull rod 92 is connected to the 105 pusher rod 89, so that when movement is imparted to the rod 92 from left to right, either one of the fingers 90 and 91 may be in position to receive an impulse from one of the pusher fingers, either 68 or 70. Normally, 90 and 91 will be out of line with the fingers 68 and 70 through the medium of the spring 93, which has a normal tendency to press the rod 92 to its extreme limit toward the left, but through the action of 110 a rock shaft 94 connected to the pull rod 92 and a lever 95 (see Fig. 6) actuated by a cam, the rod 92 may be moved against the action of the spring so as to aline either 115 the main finger 90 with the pusher finger 68, or the offset finger 91 with the pusher finger 70, the position being responsive to the cam hereinbefore mentioned, and which will be described in detail later. 96 is a 120 pusher rod adapted to aline with the pusher 125 130

finger 72 through the medium of a pull rod 97, and 98 is a similar pusher rod adapted to align with the finger 80 through a pull rod 99, 97 and 99 being provided with 5 springs similar to that designated 93. The rods 97 and 99 are provided with rock shafts, 100 and 101, respectively, and these rock shafts move in response to the levers 102 and 103, which are actuated by the cams 10 on the cam plate. The pusher rod selected for illustration is designated in Fig. 1 as 98, the construction of this being similar to all of the pusher rods hereinbefore mentioned, with the exception of 89, which is 15 provided with the offset 91. The ejecting mechanism that each pusher rod actuates is identical in construction, with the exception of the dime ejecting mechanism, which follows the general construction but 20 which is slightly modified to permit the ejection of two dimes under certain conditions. By reference to Fig. 1 it will be observed that the dogs are provided with upstanding projections 104 having beveled 25 edges, so that when a coin is inserted in one of the pushers, for example, 48, and the handle 55 is turned, the dog will be depressed so as to impart a swinging movement either to the shaft to which it is attached or to the sleeve, as the case may be. 30 As each dog is designed to cause one of the pusher fingers to be depressed, some one of the pusher rods will be actuated. If 98 is actuated against the spring 105, it will tilt 35 the tail 106 of the pivoted lever 107 and move the detent 108 out of engagement with the opening 109 in the floor 21 and against the action of its spring 110. The detent 108 is pivoted to a coin ejector, a detail of one of 40 which is shown in Fig. 12 as comprising a plate 111, with a coin opening 112 therein, the detent 108 being pivoted to said plate 111 at 113. Inasmuch as the detent is pivotally secured to the plate 111, any movement 45 imparted to the detent in a longitudinal direction must be partaken of by the plate, therefore, when the plate 106 is depressed to move the free end of the detent 108 out of engagement with the opening 109, this 50 free end will be in a position to permit the arm 114 on shaft 54 to come in contact therewith, and as the shaft 54 is rotated to move one of the coin slides toward the chute, the arm 114 will impart a sliding 55 motion to the plate 111. By reference to Fig. 12 it will be observed that the plate 111 is provided with an elongated portion or constricted projection 115 having a positioning opening 116 therein, and that the 60 projection 115 slides within a guide 117, (Fig. 15) in which there is a spring-pressed friction pin 118 adapted to bear against the face of the projection 115 to apply slight tension thereon, and that the point 65 119 of the pin 118 is adapted to engage the

opening 116 to properly position the plate when it is restored to its normal inactive position by the spring 120. Inasmuch as the opening 112 in the plate 111 will be immediately beneath its registering magazine when the pin 118 engages opening 116, a coin will be received from the magazine in the opening 112, and as a result, when the plate 111 is projected forward toward trough 34, a coin from said plate will be deposited in said trough. The construction of the coin ejector just described is substantially that used for ejecting nickels, quarters and half dollars. The dime ejecting mechanism, however, while following the same generic construction, is modified to the extent of providing means for ejecting either one dime or two dimes, and this I will now proceed to describe: In Fig. 9 the ejector 111^a, which normally moves back and forth to eject a dime, is substantially the same in construction as those ejectors utilized for coins of other denominations, with the exception that on one edge of the ejector plate is a notch 121. This notch is to be utilized in connection with other mechanism for temporarily locking a superposed plate 111^b on top of 111^a when it is desired to eject two dimes instead of one; the plate 111^b is devoid of the projection 115, and it is provided with edge notches 122 and 123, the notch 123 being at times in line with notch 121, and adapted to receive the locking bolt or projection on a lever, whereby the two plates may be locked together. The notch 122 is for the purpose of receiving a projection on the locking bolt, whereby the plate 111^b will be held stationary when only one dime is to be ejected, and permit the operation of the ejector plate 111^a in the usual manner. The locking mechanism whereby the two plates may be locked together and unlocked is best shown in Figs. 7, 8, 11 and 16. To one side of the plates 111^a and 111^b is a bar 124 spaced from the floor 21 by the spacing blocks 125 and 126. The bar 124 runs substantially the length of the effective part of the ejector 111^a, and slidably secured on said bar is a sleeve block 127 carrying a pivoted lever 128, at one end of which is a dog 129, the thickness of which is substantially equal to the width of the plates 111^a and 111^b, and said dog is adapted to engage both the notches 121 and 123. Normally, however, the dog will be held out of engagement with said notches by the spring 130. At the other end of the lever is a tooth 131, offset in a higher plane than the plane in which plate 111^a moves, and said tooth is adapted to normally engage the notch 122, so that the plate 111^a may be moved by its mechanism without carrying with it the plate 111^b. In order to release the tooth 131 from the notch 122 and cause the dog 129 to engage both

the notches 121 and 123, it is necessary that the dog be moved on its pivot against the action of the spring 130. This may be accomplished by providing the free end of the dog 129 with an inclined edge 132, against which one end of a lever actuating finger 133 may be caused to abut. The lever 133 is fixed on a vertical shaft 134, which extends upwardly, and through the link mechanism 135 (Fig. 4) is connected to a pivoted rod 136, the tension spring 137 being so disposed that the tendency of the finger 133 will be to move away from the inclined edge 132, and said lever is provided 10 at its end adjacent to the cam slide with a rule-joint 138, that is to say, a joint which breaks in one direction only, and the end of the lever 136 is adapted to be moved against the action of the spring at suitable 15 periods by contact with the projections 139 and 140 on the cam slide 141. In the position shown in Fig. 4, the cam projection 139 is in position to actuate the lever 136, and through the mechanism which it controls, to lock the two plates 111^a and 111^b together, because that is the position that the cam slide will assume when six fares are to be paid and a half dollar is inserted in the machine, because it then becomes necessary to lock the two dime slides together so 20 that twenty cents change will be delivered. This function is illustrated by way of example in Figs. 7, 11 and 16. Bar 124 has a notch 124^a while the lever 128 carries on 25 lock end 129, a roller pin 128^a adapted to enter notch 124^a. When dog 129 locks both slides 111^a and 111^b at 121 and 123, it will be held in locking position by roller pin riding on edge of bar 124 and will remain 30 locked until two dimes have been ejected and return of slides allows roller pin 128^a to fall into notch 124^a under the action of spring 130 and thereby lock upper slide 111^b. The details of the change making, 35 however, will be specifically described hereinafter.

Adjacent to the rock shaft 94 is a pivoted lever 142, which is connected at one end to the clutch sleeve 73, which carries the bridging bar 86, and this lever may be actuated in response to a cam on the cam slide 141, the operation being timed to throw the clutch sleeve 73 out of engagement with dog 76 when five fares are to be paid and a 40 quarter is inserted, so that at this time the dog 76 will be loose on shaft 65 and a quarter may be inserted in its proper opening without causing actuation of any of the pusher rods to deliver coins of less denomination. 45 The lever 142 is normally retracted by a spring 143.

The rock shafts 94, 100 and 101 and the levers 136 and 142 all being responsive to the action of the cam slide, I will now proceed to describe said cam slide. This slide

is provided on its under side with the cams. Cam 144 (see Figs. 4 and 6) is provided with a relatively deep portion 145 and a relatively shallow portion 146, and this cam aligns with certain other cams 147, 148 and 149, all of which are adapted at proper intervals to actuate the rock shaft 94. The cams for rock shaft 100 are designated 150 and 151. The longer cam 152 is adapted to actuate the rock shaft 101. The cam 153, 75 near the inner edge of the plate 141, is adapted to actuate the lever 142. The bringing of these cams into operation will be coincident with the indication of the pointer 154 on the handle 155 projecting through 80 a slot in the casing and integral with the slide 141, the pointer 154 being movable along a scale 156 which indicates the number of passengers for which fares are to be paid. If desired, the slide 141 may have a 85 register actuating projection 157 (see Fig. 4), which may consist of a rack engaging a pinion to actuate a suitable fare register 158, so as to check up the indicator. Attention is here called to the fact that the pusher rods are pivoted intermediate their ends at 98^a, so that the upper parts of the rods may be swung to right or left to bring them into and out of alignment with their pusher fingers without disturbing the portion marked 95 98^b, which effects the thrust for the members 107.

The description up to this point deals with the means for delivering the proper amount of change where a single coin is deposited for fares aggregating not more than the value of the deposited coin. The same mechanism will serve where two coins of the same denomination are deposited to cover fares aggregating more than the value of 100 one of said coins, but only when the number of fares is an even number. In such transactions the indicator may be set as for two successive transactions, each of a value which is one-half of the whole. For example, if two quarters are presented for six fares, the indicator being set as for three fares, the device heretofore described will function once for each quarter, so as to deliver twenty cents change in two equal installments. When, however, an uneven number of fares are to be taken out of two coins of the same denomination, as three fares from two dimes, or seven or nine fares from two quarters, a different problem is presented. For such contingencies I provide means whereby the function, which normally follows the deposit of a coin, of calling into play an ejector or ejectors, will not be duplicated but only one coin will so 115 function. For example, if the indicator is set for seven fares, and two quarters are deposited, one of the quarters will idle; that is to say, no ejectors will be actuated by the insertion of one of the quarters, but the in- 120 125 130

sertion of the other quarter will cause the functioning of the dime and nickel ejectors. To accomplish this, the construction shown in Figs. 5^a and 5^b may, for example, be employed. Referring to Figs. 5, 5^a and 5^b, dog 76 acts as idler to the first quarter inserted when the indicator 154 (Fig. 2) has been moved to six or more fares, because after the value of one quarter (five fares) has been 5 passed by the indicator, cam 153 of cam slide 14, will engage lever 142, thereby disengaging clutch sleeve 73 from sleeve 75. A pin 75^a having a head 75^c is positioned in a recess in sleeve 75, and a compression spring 15 75^b tends to throw pin 75^a toward clutch sleeve 73, but pin 75^b, projecting from shaft 65 and engaging a notch in pin 75^a holds the latter normally retracted. A short pin 75^d on head 75^c projects through a slot in sleeve 20 75 and prevents rotation of pin 75^a. On the slightest movement of dog 76, as when the first quarter passes over it, pin 75^a will be released and its head 75^c will be pressed against the clutch surface of sleeve 73 until 25 dog 76 returns to normal position, whereupon pin 75^a will move forward into operating relation to the step on sleeve 73. Consequently, when the second quarter is inserted and actuates dog 76, shaft 65 will be 30 rotated and the appropriate nickel and dime ejectors will be actuated. The pin 75^a is returned to normal position and locked by closing of clutch 73. The spring holding up dog 76 will also hold 75^a against pin 75^b, 35 thereby locking same.

For dimes, I prefer to employ the device shown in Figs. 18, 19 and 20, in which, when the indicator is adjusted to indicate 3, 5, 7 or 9 passengers, a rack 141^a on the 40 under surface of cam plate 141 has imparted such rotation to the pinion 171 on the shaft 172, that the traverser nut or carriage 173, fitted to the quick-pitch screw thread 174, will have acted through the lever 175, pin 45 176, shifter rod 177 and fork 177^a, to displace to the left block 178 which is keyed on shaft 181. The finger 179 on block 178 will be engaged by the first, second, third or fourth steps on clutch block 180 when the 50 latter is rotated around shaft 181, the particular step engaged depending upon the extent of the leftward displacement of block 178 on shaft 181. Clutch block 180 is of 55 segmental shape and is mounted on ratchet wheel 182. The ratchet wheel is loosely mounted on shaft 181 and is held against longitudinal movement by collars on each side, rigidly secured to said shaft, as for example, by means of set screws. Pawl 189, 60 depending from detent 71, will cause the rotation of ratchet wheel 182 a distance corresponding to the depth of one tooth, provided, however, that the position of lever 188 permits the engagement of pawl 189 65 with ratchet wheel 182. A rocking move-

ment is imparted to lever 188 through link 187, which is reciprocated up and down as a result of the co-action of shaft 186 with cam rack 185. A spring 186^a tends to depress shaft 186 and a cam roller 186^b is 70 provided at the lower end of said shaft. A ratchet lock 183 has a finger 184 resting upon cam rack 185, so that ratchet lock 183 will engage ratchet wheel 182 when finger 184 drops into a recess of cam rack 185 and 75 will be raised out of engagement when finger 184 rides up on one of the cams. An arm 190 is rigidly secured to shaft 181 and has pivoted connection at its outer end with pusher rod 191 (see Fig. 13). A forked 80 foot 192 on pusher rod 191 engages a step 193 on pusher rod 89. Consequently, when shaft 181 is rotated so as to depress arm 190 and pusher rods 191 and 89, a nickel 85 will be ejected in the manner previously described. A spring 177^b serves to return shifter rod 177 and connected parts to normal, and this action is assisted by the weight of clutch block 180.

The operation of the device just described 90 is as follows: When the indicator 155 is set for an even number of passengers, cam roller 186^b will rest in one or the other of the recesses of cam rack 185, in which position of the parts pawl 189 will be held out 95 of engagement with ratchet wheel 182. If the indicator is set for three passengers, block 178 will have been shifted to the left, but only through a distance which is insufficient to cause finger 179 to clear the 100 first step on the clutch block 180. In this position, however, cam roller 186^b will be raised on to a cam of cam rack 185, thereby releasing pawl 189 through the lever system 186, 187 and 188, and permitting said 105 pawl to engage ratchet wheel 182. With the parts in this relation, if two dimes be successively inserted, the first will cause a depression of detent 71, and consequently, a one-tooth rotation of ratchet wheel 182 110 and block 180. This movement will bring finger 179 into engagement with clutch block 180, so that upon the insertion of the second dime and the consequent one-tooth advancement of ratchet wheel 182, clutch 115 block 180, and with it block 178 and shaft 181, will be rotated to cause the ejection of one nickel. Similarly, when the indicator is set for five fares and three dimes are inserted, ratchet wheel 182 will be rotated 120 two steps before finger 179 comes into engagement with clutch block 180, by reason of the fact that on this occasion block 178 has been shifted to the left a distance which causes finger 179 to clear the first 125 step on clutch block 180, so that the nickel-ejecting mechanism is not actuated until the second step on clutch block 180 engages and displaces finger 179. When the indicator is set for seven fares and four dimes are pre- 130

sented, the first three dimes will idle and the fourth dime will cause the ejection of a nickel.

Inasmuch as the change-making machine herein described is designed to make change for denominations of a half dollar and less, no pusher finger is provided for releasing a half dollar, but it is obvious that under certain conditions it may be desirable to release a half dollar from its magazines; for example, where the amount of fares is less than ten cents and the passenger presents money of greater denomination than a half dollar, for example, a dollar. A pusher rod similar to those heretofore described, and an ejector may be provided, which will be manually operated through the medium of a key 159, which may be depressed to actuate its pusher rod 160 without in any way disturbing the rest of the mechanism; that is to say, the half dollar ejector may be operated quite independently of the rest of the mechanism through the medium of the key 159.

It is to be understood, of course, that the magazines are to be filled by the conductor and then replenished from time to time, if desired, from the contents of the drawer, the top of the casing being hinged for this purpose. The money actually paid into the machine invariably is deposited into the drawer, and money paid out of the machine invariably is ejected from the magazines.

The operation of the cams and the coöperative mechanism can best be understood by following out in sequence the operations.

Suppose one fare is to be paid and a nickel is inserted in the nickel slide. The conductor moves the indicator 154 to 1 on the scale 156, and inasmuch as the indicator is on the slide 141, cams 144, 150 and 152 will be brought to operating positions. However, there is no dog projecting through an opening in the nickel slide, so no operation of the pusher fingers can take place. The nickel will simply drop into the magazine, or if full, into the drawer. If one fare is to be paid and a dime is inserted in the dime opening, the indicator is still at 1 with the cams 144, 150 and 152 in operative positions, with the offset portion of pusher 89 under the pusher finger 70. The dime will cause the dog 71 to turn sleeve 69, forcing down finger 70 so as to depress pusher rod 89, or as indicated in Fig. 1, 98, so that the detent 108 is moved out of its opening in position to be engaged by 114. As the handle 55 is swung anti-clockwise, the dime slide, as well as all the other slides, will be pushed forward, but inasmuch as the dime slide is the only one containing a coin, its particular dog 71 will respond and the nickel ejector mechanism will be operated to eject one nickel into the coin pan 35. If a quarter is inserted and one fare is to be paid, pro-

jection 139, which has been moved against rod 136, will have locked 111^a and 111^b together, but dog 76 will cause a rotation of shaft 65, causing fingers 68 and 72 to be depressed. 72 being in line with its pusher rod, will cause the dime ejecting mechanism to operate, and as 111^a and 111^b are locked together, two dimes will be ejected. At the same time that the finger 72 is depressed, the finger 68 will be depressed, but as previously explained, the finger portion 90 is not now in line with 68, therefore the nickel actuating mechanism cannot be operated. Therefore, it will be apparent that if one fare is to be taken out and a quarter is inserted in the machine, two dimes or twenty cents will be delivered to the depositor. If a half dollar is inserted in the machine, the dog 81 will be operated, depressing the fingers 80, 72 and 68. The finger 68 is not in line with any portion of the pusher rod 89, but pusher rods 96 and 98 are in line with their pusher fingers and the two dime slides will lock together, therefore a quarter and two dimes will be delivered. If one dollar is handed to the conductor, it will be necessary for him to depress the key 159, and as the offset 161 (Fig. 17) of the key comes in contact with projection 162 on dog 81, dog 81 will be depressed simultaneously with the pusher rod 160 rigid on key 159, so that a half dollar will be ejected, and in addition, the dog 81 will cause the same operation to take place with respect to the remaining ejectors that took place when a half dollar was inserted, so that the depositor receives a half dollar, a quarter and two dimes.

If two fares are to be paid, the conductor moves the indicating pointer 154 opposite the numeral 2 in the scale 156. As a result, the shallow part of cam 144 actuates the rod 94 to impart movement to pull rod 92, so that the offset 91 will move out of alignment with second pusher finger 70, so that the pusher finger 70 could not actuate the nickel pusher rod, even though the dog 71 causes a partial rotation of the sleeve 69, therefore no change will be delivered. If a quarter is inserted, the dog 76 will be depressed, causing a depression of fingers 68 and 72, and as the pusher rods for the dimes and nickels are in alignment with said pusher fingers, one dime and one nickel will be ejected. If two fares are to be paid and a half dollar is inserted, the dog 81 will be effective in depressing pusher fingers 68, 72 and 80, so that a quarter, a dime and a nickel are ejected, as change. If an amount in excess of a half dollar is tendered the conductor, and it becomes necessary to eject a half dollar in change, this can be accomplished as heretofore described, by depressing the key 159, this operation being performed whenever it is necessary to release 130

a half dollar in addition to the change automatically ejected during the operation of the machine. During all of the two-fare operations, the projection 139 is out of engagement with the end of lever 136, because the shifting of the cam slide from one-fare position to two-fare position has moved the projection past the end of the lever 136, and for that reason the plates 111^a and 111^b 10 are not locked together, only the lower slide 111^a being effective, and therefore only one dime will be delivered as a result of each reciprocation of the slide 111^a.

When the cam slide is moved up to 3 on scale 156, the lever 95 for shaft 94 will have passed off the cam 144, so that the nickel pusher rod will not be operated, because it will not be in line with either of its pusher fingers. The dime and quarter pusher rods 20 are in alignment with their respective fingers only, so that a dime will be delivered in exchange for a quarter, or a dime and a quarter in exchange for a half dollar.

If the indicator finger 154 is moved up to 4, for four fares, the lever 95 will be engaged by the cam 147, and lever 102 will have dropped off cam 150, although lever 103 will still be in engagement with cam 152. As a result, the main portion of the nickel pusher 30 rod is under the first pusher finger 68, the dime pusher rod is out of its pusher finger, and the quarter pusher rod is in line with its pusher finger. As a result four nickels introduced into the machine for four fares will 35 simply be deposited in the magazine or the drawer without operating anything. Two dimes or two nickles and one dime will also be ineffective to operate anything, for while the dime dog may respond to a coin, the 40 pusher finger which it actuates will not be in line with its pusher rod. If a quarter is inserted, the pusher finger 68 will be operated to release one nickel. If a half dollar is inserted, pusher finger 80 and pusher 45 finger 68 will be operated to release a quarter and a nickel.

If the indicator is moved up on the scale 156 to indicate five fares, the cam 153 will come in contact with rod 142 to throw the 50 clutch sleeve 73 out of engagement with the clutch face on the dog 76, therefore the dog 76 may idly rock on shaft 65 without affecting any other mechanism. As cam 150 is not now operating anything, the dime mechanism 55 will be inoperative, although the quarter pusher rod 98 is in line with its finger 80. The only pusher rod which may now be operated is the quarter pusher rod, and this only on presentation of a half dollar, and the only time change will be delivered is when a half dollar is inserted and one quarter is released.

If the indicator is moved to indicate six fares, the clutch will still be out, because the 60 cam 153 is long enough to hold the clutch out

from five fares to ten fares. Cam 152 will have dropped off end of lever 103, so that the quarter pusher rod will not be operating. Cam 151 will have picked up the lever 102, so that the dime pusher rod will be under its 70 pusher finger, and projection 140 will have moved into engagement with the end of lever 136, and through the mechanism actuated thereby, lock the slides 111^a and 111^b together, so that inasmuch as the dime pusher 75 rod is the only one operating, only two dimes can be delivered.

If seven fares are to be paid, the movement of the slide 141 will have caused the projection 140 to move out of engagement 80 with 136, so slide 111^b will not operate when slide 111^a is operated. At this time, however, the pusher rod for the dime is in line with its finger, also the pusher rod for the nickel is in line with the finger 68. Therefore no ejection can take place until a half dollar is inserted, but upon the insertion of a half dollar and the operation of the handle 55, a dime and a nickel will be delivered to the coin pan 35.

If eight fares are to be paid, the movement of the slide 141 will release the cam 148 from engagement with lever 95, but cam 151 will still be effective to retain the dime pusher rod under its operating finger. No 95 other ejector will be operative, therefore, no delivery of change can take place unless a half dollar is inserted and the handle 55 turned, whereupon one dime will be delivered.

If nine fares are to be paid, all pusher rods will be inoperative, except the nickel pusher rod, on account of cam 149 engaging lever 95. No change will be delivered unless a half dollar is inserted, and upon turning the 105 crank handle 55 one nickel will be delivered to the coin pan 35.

If ten fares are to be paid, nothing takes place, as the movement of the cam slide to permit the indicating pointer to rest opposite 110 scale 156 will be effective in neutralizing all of the mechanism.

The interior of the the change counter will be accessible to the conductor at any time, so that change may be removed from the 115 drawer as occasion demands, and the depleted magazines may be replenished if it becomes necessary, but the amount of fares paid in will be indicated on the register 158, access to which will not be possible to the 120 conductor.

Claims.

1. In a change making machine the combination of a plurality of coin ejectors, each adapted to eject coins of a denomination different from those of the others, separate coin ejector actuating mechanisms, means responsive to an inserted coin for operating the actuator mechanisms of coins of a lower denomination than that of the inserted coin, 125 130

and means for moving the actuator mechanisms out of line with their operating mechanisms.

2. A change-making machine comprising 5 coin ejectors, means for feeding coins to the ejectors, reciprocatory rods for actuating said ejectors, a shaft, selectors on the shaft for engagement with the rods upon the insertion of a coin, and means for rendering 10 said selectors operative.

3. In a change-making machine a casing, coin magazines in said casing, coin ejector slides beneath the magazines, coin receiving slides above the magazines, reciprocatory 15 rods for permitting actuation of the coin ejecting slides, means responsive to the coin receiving slide for actuating said rods, and a pull handle for causing the selected coin ejecting slides to operate.

20 4. In a change-making machine an ejector comprising a slide, a dog on said slide engaging a rigid part of the machine, a pivoted lever for moving said dog out of engagement with the rigid part of the machine, a rod for actuating said lever, means for imparting movement to said rod, a pull handle, and means controlled by the pull handle for engagement with said dog to impart movement to said slide.

25 30 5. In a change-making machine a plurality of change ejectors, means for normally locking the ejectors against movement, a plurality of rods for releasing the locking means, pusher fingers for actuating 35 said rods, means responsive to a coin for permitting the pusher fingers to operate, and means for actuating the ejectors after they are released from the locking mechanism.

40 45 6. In a change-making machine a plurality of coin ejectors, means for normally locking said ejectors against movement, separate releasing rods for each locking means, one of said rods having a bifurcated end, means for independently engaging the ends of the respective rods, and means for permitting actuation of said engaging means.

50 7. In a change-making machine coin ejectors, means for normally locking said ejectors against movement, means for actuating said ejectors when the locking means is released, rods for releasing the locking means, a shaft, means on the shaft for separately 55 engaging each rod, said engaging means being normally out of line with said rods, and means for independently alining the rods with their actuating means.

30 8. In a change-making machine coin ejectors, means for actuating said coin ejectors, means for normally holding the ejectors against movement, means for releasing selected ejector locking means upon the insertion of coin, and means for increasing the 65 ejecting capacity of one of the ejectors.

9. In a change-making machine coin ejecting means, a fare indicator, a cam slide supporting the movable part of the fare indicator, means responsive to the cams on the slide to position certain ejecting mechanisms for actuation, and coin carrying slides operative upon the insertion of coins to cause positive actuation of the ejecting mechanisms.

10. In a change-making machine a casing, 75 coin slides provided with notches, slide detents engaging said notches, pusher fingers responsive to movement of the detents, shiftable rods movable into and out of line with said pusher fingers, coin ejector locking 80 mechanisms controlled by said rods, coin ejectors, and means for actuating said ejectors simultaneously with the actuation of the slides.

11. In a change-making machine a plurality of coin ejectors normally inoperative, means for rendering said ejector operative, comprising laterally shifting rods, pusher fingers for said rods, detent dogs adapted to be depressed to actuate said pusher fingers, and coin carrying slides to actuate the 90 detent dogs.

12. In a change-making machine a coin ejector comprising a slide, a dog on said slide normally engaging a rigid part of the 95 machine, means for releasing the dog from engagement with the rigid part of the machine, a shaft, and an arm on said shaft for engaging the dog to impart a sliding movement thereto.

13. In a change-making machine a coin ejector comprising a slide, a dog on said slide normally engaging a rigid part of the machine, means for releasing the dog from engagement with the rigid part of the machine, a shaft, an arm on said shaft for engaging the dog to impart a sliding movement thereto, a coin receiving slide, and a link connection between the ejector slide, the coin receiving slide and the shaft.

14. In a change-making machine a casing, a coin receiving slide in the top of the casing, a detent engaging said slide and movable in response to a coin deposited in the slide, a pusher finger, the movement of which responds to the movement of the detent, a coin ejector, a locking mechanism therefor, means for releasing the locking mechanism, including a reciprocatory rod having a shiftable end, a shift rod connected to said end, a rock shaft having connection with one end of the rod, a cam slide for actuating said rock shaft, a connection between the coin slide and the ejector, and a pull handle connected to said connection.

15. In a change-making machine, coin ejectors, means whereby deposit of a coin induces ejection of a coin or coins, a passenger-number indicator selecting the ejectors influenced by the deposited coin, and means 130

- negativating the effect of one of two identical coins deposited in a single transaction, said last named means being controlled by the passenger-number indicator.
- 5 16. In a change-making machine, coin ejectors, means whereby deposit of a coin induces ejection of a coin or coins, a passenger-number indicator selecting the ejectors influenced by the deposited coin, and means negativating the effect of one of two identical coins deposited in a single transaction, said last named means being controlled by the passenger-number indicator and comprising a pair of coacting members through which the influence of the deposited coin is exerted, and means comprising a lever system, a 30 traverse, and a shaft having a feed thread for said traverser and rack and pinion connection with the passenger-number indicator for relatively adjusting said coacting members to develop lost motion between 35 them.
- 10 17. In a change-making machine, coin

ejectors, means whereby deposit of a coin 20 induces ejection of a coin or coins, a passenger-number indicator selecting the ejectors influenced by the deposited coin, and means negativating the effect of one of two identical coins deposited in a single transaction, said 25 last named means being controlled by the passenger-number indicator and comprising a pair of coacting members through which the influence of the deposited coin is exerted, and means comprising a lever system, a 30 traverse, and a shaft having a feed thread for said traverser and rack and pinion connection with the passenger-number indicator for relatively adjusting said coacting members to develop lost motion between 35 them.

GEORGE J. BROCKHAGEN.
